UNITED STATES PATENT OFFICE.

EDWIN L. SPRAGUE, OF BOSTON, MASSACHUSETTS.

SHOE.

SPECIFICATION forming part of Letters Patent No. 283,035, dated August 14, 1883.

Application filed April 20, 1883. (No model.)

To all whom it may concern:

Be it known that I, EDWIN L. SPRAGUE, of Boston, county of Suffolk, State of Massachusetts, have invented an Improvement in Shoes, 5 of which the following description, in connection with the accompanying drawings, is a specification, like letters on the drawings representing like parts.

This invention relates to the class of shoe represented in United States Patent No. 239,005, and has for its object to render the top more elastic, thus permitting it to more readily adapt itself to the ankle, and to obviate the objectionable extension of the so-called "strengthening-strips" of the fastening-flap across the foot below the ankle-bone, where, in many instances, it makes an objectionable pressure. In the patent referred to that portion of the fastening-flap containing the button-holes, as well as 10 the attached elastic portion, is bound at the lower edge by a strengthening-strip extended across the inner side of the foot below the ankle-bone, where it is connected directly with the front portion of the top and produces an uncomfortable pressure at such point because 15 of its thickness. Binding the lower edge of the fastening-flap renders the same inelastic at its lower edge, and makes it hard for the wearer of the shoe, if at all a close fit, to button the lower 20 button of the fastening-flap, and when buttoned draws uncomfortably across a very tender part 25 of the inner side of the foot. To obviate this close fit and uncomfortable pressure manufacturers are liable not to fit the shoe with sufficient care, and consequently leave the lower 30 thickened edge of the fastening-flap too long, so that it bulges outwardly, destroying the appearance of the shoe and leaving a gap for the entrance of dust, &c., into the shoe. A shoe 35 of this class to be desirable should fit as snugly and carefully as a Congress gaiter, and the elasticity of the top should be the same at each side in order to equalize the pressure of the shoe at the ankle. To overcome this difficulty 40 I have made the fastening-flap of a piece of elastic fabric having two selvage edges and extended from the bottom to the top of the flap, so that the selvage edges form portions of the bottom and top of the flap, and along the outer 45 edge of the said fabric I have stitched a piece of leather provided with button-holes, thus leaving the flap free to stretch along its top 50

and bottom and adapt the top of the shoe or the part above the vamp and quarter to the ankle of the wearer.

55

Figure 1, in side elevation, represents a shoe embodying my invention, the flap being closed or buttoned; and Fig. 2 a similar view, with the flap unbuttoned and opened.

The vamp *a*, quarter *b*, sole *c*, and front portions, *d*, of the top, and back portions, *e*, and elastic gore *f*² at the closed side of the shoe, are all substantially as in the patent referred to; but the elastic portion or gore *A* in the fastening-flap differs from that marked *f*¹ in the said 60 patent in that it has selvage edges *r*, *s* at bottom and top, which are free to stretch and enable the fastening-flap to adapt itself to the size and shape of the ankle and inner side of the foot and always insure a close fit at the lower edge of 65 the said flap without objectionable pressure. The fastening-flap has one edge of its elastic portions *A* stitched to the front piece, *d*, of the top at *m*, and at the other side edge of the said elastic portion is a buttoning-piece, *B*, of 70 leather, which is stitched to it at *n*, as shown 75 in Fig. 1.

The button-holes are marked *h*, and the buttons *p*, leaving the elastic fabric *A* free to stretch at bottom and top and connecting the 80 buttoning-piece *B* only with the elastic fabric *A*, and not directly with the front piece, *d*, as in the said patent, by a strengthening-strip, 85 leaves the part *A* of the buttoning-piece free to stretch at its upper and lower edges, as described, as much as may be needed.

At the upper edge of the quarter, and between the edges of the front and back pieces, *d*, *e*, of the top, and at the lower end of the space or opening at the inner side of the shoe 90 when unbuttoned, there is a small elastic gore, *g*, the upper portion of which is overlapped by the lower selvage edge, *s*, of the elastic portion *A* of the flap, so that at such point there are two thicknesses of elastic fabric when 95 the shoe is buttoned. If the flap herein shown were provided with the so-called "strengthening-strip" of the shoe represented in the patent referred to as enveloping the lower end of the elastic portion of the flap and connecting 100 the piece of leather containing the button-holes with the front part of the top, then the gore-piece *g* could not yield after the button-flap was engaged with a button; but with a flap

constructed as herein shown, and having its lower edge free to be stretched across the ankle to the lower button of the buttons *p*, the gore *g* is at all times free to yield to the ankle together with the elastic portion *A*. Leaving the lower edge of the elastic part *A* and selvage edge free to yield and stretch to fit the ankle when the flap is buttoned, I am enabled to dispense with the extra cost attendant upon fitting the shoe to ankles of particular size, as when the lower edge of the flap is bound and does not stretch, and I am also enabled to save stock, thus cheapening the cost of construction of the shoe and enabling it to be made by ordinary workmen.

Instead of button-holes and buttons, I may employ any other usual fastening devices.

The top pieces, *d e*, and the buttoning-flap *B* may be made of cloth or any usual material commonly employed in shoes.

I am aware that it is not new to add to an otherwise finished and complete boot a top or anklet attached above the usual gaiter-top by extending the heel-piece or providing it with a narrow projecting tongue, to which tongue elastic flaps are attached, so that they will overlap the usual gaiter-top, and which flaps are provided with leather or other edges and fastening devices thereon uniting at the front of the leg to protect the stockings; but this top or anklet does not constitute the fast-

ening device of the shoe, as in my invention, and I expressly limit my invention to a shoe the fastening-flap whereof is constructed as herein set forth.

35

I claim—

1. In a shoe having a sole, *c*, vamp, and quarter, and top pieces, *d e*, the flap for fastening the shoe, composed of an elastic fabric having selvage edges *r s*, and an attached button-piece, *B*, the parts being joined together, as described, leaving the selvage edges of the elastic fabric *A* free to yield to the shape of the ankle, substantially as set forth.

40

2. In a shoe having a sole, *c*, vamp, and quarter, and top pieces, *d e*, the flap for fastening the shoe, composed of an elastic fabric having selvage edges *r s*, and an attached button-piece, *B*, the parts being joined together, as described, leaving the selvage edges of the elastic fabric *A* free to yield to the shape of the ankle, and having an elastic gore, *g*, overlapped by the lower edge of the fastening-flap, substantially as set forth.

45

In testimony whereof I have signed my name to this specification in the presence of two subscribing witnesses.

EDWIN L. SPRAGUE.
